UNITED STATES PATENT OFFICE.

JACOB HUTHER, OF ST. LOUIS, MISSOURI, ASSIGNOR TO JOHN C. HACKETT,
OF BELLEVILLE, ILLINOIS.

TRACE-FASTENER FOR WHIFFLETREES.

SPECIFICATION forming part of Letters Patent No. 390,171, dated September 25, 1888.

Application filed January 11, 1888. Serial No. 260,386. (No model.)

To all whom it may concern:

Be it known that I, JACOB HUTHER, of the city of St. Louis, in the State of Missouri, have invented a certain new and useful Improvement in Trace Fasteners and Detachers for Whiffletrees, of which the following is a full, clear, and exact description, reference being had to the accompanying drawings, and in which—

10 Figure I is a front view of a vehicle with my improvement applied. Fig. II is an enlarged view showing the outside of the fastener. Figs. III and IV are sections taken on line III IV, Fig. II, Fig. III showing the fastener in using position and Fig. IV showing it open to release the trace or tug.

15 My invention relates to an improved trace-fastener for singletrees from which the tug or trace may be readily detached when desired; and my invention consists in features of novelty hereinafter fully described, and pointed out in the claims.

20 Referring to the drawings, 1 represents part of a whiffletree, into which is inserted a shank, 2, at each end.

25 3 represents a plate pivoted to the shank 2 at 4, and which has perforated enlargements 5 to receive the journals 6 of a yoke, 7, which is provided with a loop, 8, and a tongue or projection, 9. When the yoke is closed, the tongue or projection 9 fits in a perforation or hole, 10, in the outer end of the plate 3, (see Fig. III,) and when the free end of the yoke is pulled away from the plate, as shown in Fig. IV, the 30 tongue or projection is withdrawn from the hole or perforation. When in the using position, the tongue or projection passes through a hole in the tug or trace 11, as shown in Fig. III, and thus connects the tug or trace to the 35 whiffletree, and when it is pulled out, as shown in Fig. IV, the tug or trace is released or detached. The yoke is held in using position by means of a spring, 12, secured to the plate 3,

preferably by a projection, 14, formed thereon, and which receives the spring and is riveted upon it, as shown in Fig. IV. The free end of the spring bears against a lip or projection on the journals 6 of the yoke 7, as shown in Figs. II, III, and IV, and thus tends to hold the yoke in its closed position. In case of an accident, or when it is desired to detach the tugs or traces from the whiffletree, the yokes 7 on the respective ends of the whiffletrees are moved into the position shown in Fig. IV, and this may be done simultaneously by means of a strap, 16, (see Fig. I,) which connects the yokes, and to which is connected a strap, 17, that may pass up over the dash board of the vehicle. This arrangement provides a cheap and effective fastening and one which may be readily opened to release the tugs.

I claim as my invention—

1. In a trace fastener and detacher, the combination of the plate having a perforation, 10, and a yoke pivoted to the plate and having a tongue or projection, 9, substantially as and for the purpose set forth.

2. In a trace fastener and detacher, the combination of the plate having a perforation, 10, and spring 12, a yoke pivoted to the plate and having a projection, 15, on which the spring 12 bears, a tongue, 9, and a loop, 8, all substantially as and for the purpose set forth.

3. In a trace fastener and detacher, the combination of the shank 2, plate 3, pivoted to the shank and having a hole or perforation, 10, spring 12, secured to the plate by projection 14, riveted on the spring, yoke 7, having journal 6, provided with a lip, 15, and having a projection or tongue, 9, and a loop, 8, substantially as and for the purpose set forth.

JACOB HUTHER.

In presence of—
GEO. H. KNIGHT,
EDWD. S. KNIGHT.
